KNEE AND COLUMN MILLING AND LIKE
MACHINE

Richard Stuhlmacher, Siegmar, near Chemnitz,
Germany, assignor to Wanderer-Werke vorm.

Application May 11, 1932, Serial No. 610,719
In Germany December 1, 1930

13 Claims. (Cl. 90—18)

The invention consists in the construction of the guiding devices on the knee of a knee and column milling or like machine, by which the knee is reliably and rigidly supported.

In previously known machines of this type, the knee is guided on the column of the machine and, if necessary, by one or more pillars or supports disposed on the side opposite to the column and connected with the overarm or the base plate or with both of these members. The knee is sufficiently supported by these guides and connections to resist the stresses and distortions set up in certain directions. In use, however, stresses and distortions occur due to the cutting pressure and the weight of the work in different working positions in all three directions in space, that is, in three planes at right angles to one another. It is now found that, with heavy work and machines with large cutting capacity, the previously known guiding and supporting devices for the knee do not provide sufficient rigidity in all directions in which the forces may act. This is more particularly marked for forces and displacements in the horizontal plane. On that account, in consequence of the bending set up, either a smaller cutting capacity must be used or the accuracy of the work is lessened.

The invention provides a knee and column machine of large cutting capacity which enables heavy work to be operated with the greatest accuracy. This is obtained by the knee being guided or supported on one or both of the sides parallel to the cutting spindle by guides connected with the base plate or the column or with both these members.

The invention is represented in the accompanying drawings in several examples.

Figs. 1 and 2 are respectively a side view and a plan of a knee and column milling machine;

Figs. 3 and 4 are corresponding views of a modified construction;

Figs. 5 and 6 and Figs. 7 and 8 are corresponding views of other modifications.

In the construction shown in Figs. 1 and 2 the knee 1 is provided on both sides with lateral arms or bracing members 4 which engage with guides 5 on the sides of and running on and in the direction of the column 2. A tight guiding and supporting of the arms 4 at the column 2 is effected by screws 6, the heads 7 of which engage in grooves 8 of the column 2.

The outer part of the knee 1 opposite to the column 2 can be connected by a pillar 10 with the overarm 11, so that a great resistance is obtained in the vertical plane against forces and

distortions. The pillar 10 is guided in a bearing 12 of the knee 1 and a bearing 13 of the overarm 11. If the knee is not required to move vertically, the pillar 10 can be connected rigidly with the knee 1 and the upper arm 11 by clamping the guides 12, 13 by means of screws 14, 15. If the pillar 10 has to be moved out of the way for mounting or operating on massive work, it can be displaced upwards or downwards in the guides 12 or 13 without being removed from the machine. The vertical displacement of the pillar 10 can be effected by gearing 16, 17, 18.

In the example shown in Figs. 3 and 4, lateral bracing arms 21 are arranged at one end on the column 2 and grooves 39 are provided on the other end of each arm 21. Guides 22 on both sides of the knee 1 engage with the grooves 39 for guiding and supporting the knee 1 at the arms 21 relative to the column 2.

The arms 21 can be cast on the column 2 or constructed as separate parts and secured in any suitable manner to the column. If the arms 21 are removable from the column 2, the machine can be delivered, according to the requirements of the order received, with or without lateral bracing arms.

In order to make the guiding and supporting of the knee 1 still more rigid, the arms 21 can be connected with the base plate 23 and secured by screws 24 or other fastening devices as shown in the drawings.

Figs. 5 and 6 show a construction generally similar to that of Figs. 3 and 4. Guides 22a are provided on the free ends of the lateral bracing arms 21 and engage in grooves 39a of the knee 1 on both its sides running in the direction on the column 2.

The knee can be supported more particularly against forces and displacements in the horizontal plane, as shown in Figs. 7 and 8, by the knee being connected with the column 2 by rods 25 pivoted on the column and adjustably connected to the knee in sleeves 26. After the knee 1 is adjusted to the required height, the rods 25 can be clamped in the sleeves 26 by handles 27 and provide a lateral support between the knee and the column. The arrangement can, obviously, be effected conversely, the rods 25 being pivoted on the knee and adjustably mounted and clamped on the column.

It is preferable to use the lateral guides 5 or 22 in conjunction with the usual knee guide 3 provided on the front side of the column 2 and on the side of the knee 1 turned towards the column 2. However, it is within the scope of the

invention in particular cases to guide the knee entirely by the lateral guides 5 or 22 without using the usual guide 3.

The lateral guides 5 and 22 are preferably arranged to be finally adjusted, for example by means of wedge shaped distance pieces by known devices 30, so that the exact position of the knee is determined by the usual knee guide 3 and the guides 5 and 22 are adjusted relative to the guide 10 3 on the front side of the column.

Since the power is usually transmitted from the column to the knee for effecting the different movements of the knee 1 itself or the cross slide 40 and the work table 41 which are carried by the 15 knee 1, by a shaft provided with Cardan joints and arranged at one side of the column and the knee, other means must be provided in this case, since this space is taken up by the arms 4, 21. By a suitable construction of the arms 21, this gearing 20 for the automatic movements of the knee 1, the cross slide 40 or the table 41, can be arranged between the arms 21. In a preferred arrangement these movements are effected by a vertical shaft 35 (Figs. 4 and 6) arranged below the knee 1 and 25 coupled with the driving gear 36 of the machine. The power is transmitted from the vertical shaft 35 on the knee 1 by a gear wheel 37 which is displaceable on the shaft 35, and by other transmitting members, not shown on the drawings. The 30 vertical shaft 35 also may be arranged by the side of the knee 1 between the same and one of the lateral bracing arms 4 or 21.

I claim:—

1. A machine tool or the like, particularly a 35 milling machine, comprising a column, a knee carried by the column and movable in a vertical direction along the column, a bracing arm attached at one end at the side of the knee and at its other end at the side of the column, one 40 end of the bracing arm sliding at its point of attachment during the vertical movement of the knee, clamping means for clamping the slidably attached end of the bracing arm during the standstill of the knee, and a pair of guide-faces 45 arranged at the slidably attached end of the bracing arm for guiding and securing the knee during its vertical movement against stresses both in the direction of pressing the bracing arm against the point of attachment and in the direction of lifting the bracing arm therefrom, said guide-faces being fixedly arranged so as to be uninfluenced when loosening the clamping means.

2. A machine tool according to claim 1, in which the bracing arm is in the form of a rod rotatably connected to the column and adjustably connected to the knee by means of a tightening sleeve.

3. A machine tool according to claim 1, in which an overarm is provided on the column, and a vertical pillar is also provided connecting the knee and the overarm.

4. A machine tool according to claim 1, in which a base plate is provided and means are included for rigidly connecting the bracing arms with the base plate.

5. A machine tool or the like, particularly a milling machine, comprising a column, a knee carried by the column and movable in a vertical direction along the column, a pair of bracing arms each attached at one end at the side of the knee and at its other end at the side of the column, one end of each bracing arm sliding at its point of attachment during the vertical movement of the knee, clamping means for each bracing arm for clamping the slidably attached end of

each bracing arm during the standstill of the knee, and a pair of guide-faces for each bracing arm arranged at the slidably attached end of the bracing arm for guiding and securing the knee during its vertical movement against stresses both in the direction of pressing of the bracing arm against the point of attachment and in the direction of lifting the bracing arm therefrom, said guide-faces being fixedly arranged so as to be uninfluenced when loosening the clamping means. 10

6. A machine tool according to claim 5 in which the bracing arms are in the form of rods rotatably connected to the column and adjustably connected to the knee by means of a tightening sleeve. 15

7. A machine tool according to claim 5, in which an overarm is provided on the column, a vertical pillar is provided connecting the knee and the overarm, and means are included for guiding and supporting the knee at the overarm 20 by said pillar in each position and during the movement of the knee.

8. A machine tool according to claim 5, in which a base plate is provided and means are included for rigidly connecting the bracing arms 25 with the base plate.

9. A machine tool or the like, particularly a milling machine, comprising a column, a knee carried by the column and movable in a vertical direction along the column, a bracing arm arranged at each side of the knee and the column, said bracing arms being attached at one end to the knee and at the other end to the column and having guides at one end for securing and guiding the bracing arms at their points of attachment during the vertical movement of the knee both in the direction of pressing the bracing arms against the points of attachment and in the direction of lifting the bracing arms therefrom, an overarm provided on the column, a vertical pillar connecting the knee to the overarm, and means for guiding and supporting the knee at the overarm by said pillar in each position and during the movement of the knee. 30

10. A machine tool or the like, particularly a milling machine, comprising a column, a knee carried by the column and movable in a vertical direction along the column, bracing arms secured at one end to the column, one on each side thereof, and a guide provided on each side of the knee and having a groove therein, the other ends of the bracing arms being adjustably secured in said grooves to guide and support the knee relatively to the column during the movement of the knee. 45

11. A machine tool or the like, particularly a milling machine, comprising a column, a knee carried by the column and movable in a vertical direction along the column, bracing arms arranged at the knee, one on each side thereof running in the direction of the column, means for guiding and supporting the knee during its movement on the column by the bracing arms against stresses in all directions, a guide for the knee arranged at the front side of the column, 60 and means for adjusting said lateral guiding and supporting means relative to said front side guide. 65

12. A machine tool or the like, particularly a milling machine, comprising a column, a knee carried by the column and movable in a vertical 70 direction along the column, bracing arms secured at one end to the column, one on each side thereof, a guide provided on each side of the knee, and grooves on the other ends of the bracing arms, said guides engaging with said grooves to guide 75

and support the knee relative to the column during the movement of the knee.

13. A machine tool or the like, particularly a milling machine, comprising a column, a knee carried by the column and movable in a vertical direction along the column, and a bracing arm arranged at each side of the knee and the column, said bracing arms being attached at one end to the knee and at the other end to the column and having guides at one end for securing and guid-

ing the bracing arms at their points of attachment during the vertical movement of the knee both in the direction of pressing the bracing arms against the points of attachment and in the direction of lifting the bracing arms therefrom, and said bracing arms being in the form of rods rotatably connected to the column and adjustably connected to the knee by means of a tightening sleeve.
